UNITED STATES PATENT OFFICE.

MILTON A. MCKEE, OF WESTERLY, RHODE ISLAND, ASSIGNOR TO C. B. COTTRELL & SONS COMPANY, OF NEW YORK, N. Y., A CORPORATION OF NEW JERSEY.

HYDRAULIC PRESS.

1,094,803.

Specification of Letters Patent. Patented Apr. 28, 1914.

Application filed April 14, 1911. Serial No. 621,093.

To all whom it may concern:

Be it known that I, MILTON A. MCKEE, a citizen of the United States, and resident of Westerly, in the county of Washington and 5 State of Rhode Island, have invented new and useful Improvements in Hydraulic Presses, of which the following is a specification.

This invention relates to improvements in 10 hydraulic presses and particularly to hydraulic presses used in the treatment of printing plates.

In hydraulic presses now in use, the plunger of the press is either a part of the lower 15 platen or is at all times in contact therewith whereby the heat of the platen is readily transferred to the plunger, causing bad results due to the high temperatures to which the platen must be heated and preventing an even heating of both the lower 20 and upper platen.

My invention consists in certain improvements in the construction, form and arrangement of certain parts of the press 25 whereby the platens may be heated to the required degree while in contact with each other and separated from the plunger and also the top of the yoke to insure the double object of a uniform heating of the platens 30 by their surface contact with each other and also a minimum transfer of heat to the other parts of the press, especially the plunger and the top of the yoke, the platens being brought into contact with the plunger and 35 the top of the yoke only at the time of the pressing operation.

A practical embodiment of this invention is represented in the accompanying drawings, which illustrate the invention applied 40 to a hydraulic press of well known and approved construction.

Figure 1 is a view of the parts in front elevation, the platens being shown separated for receiving a printing plate between them, 45 the platens also being shown separated from the plunger and the top of the yoke. Fig. 2 is a partial front view of the press, showing the position of the parts when the platens are being heated preliminary to the pressing 50 operation, the platens being shown held in contact with each other and separated from both the plunger and the top of the yoke. Fig. 3 is a top plan view of the press. Fig. 4 is a partial view in side elevation with the 55 parts in the position illustrated in Fig. 1.

Fig. 5 is a detail section on a larger scale showing the means for supporting the lower platen in either its lowered or raised position independent of the plunger; the parts being in the position for supporting the 60 platen in its lower position, and Fig. 6 is a plan view of the same, the parts being shown in full lines in the position for supporting the lower platen in its lower position and in dotted lines in the position for 65 supporting the platen in its raised position.

I will only describe those parts of the press which will be necessary for a clear understanding of the construction, arrangement and operation of my invention. 70

The plunger 1 is raised and lowered in the usual manner in the cylinder 2. The usual yoke comprises the top 3, bottom 4 and connecting standards 5.

The upper platen is denoted by 6 and the lower platen by 7. The lower platen 7 is provided with the usual table 8 interposed between it and the plunger 1, which table has a forward extension 9. The upper platen 6 has a pin and slot engagement 10, 80 11, with each one of a series of brackets 12 depending from the top 3 of the yoke along the opposite sides of the upper platen 6, said brackets extending downwardly along the sides of the lower platen 7 also. 85

The lower platen 7 has a pin and slot connection 13, 14, with each of the brackets 12, which forms an auxiliary support for the lower platen when its main supporting devices, to be immediately described, are removed for any reason. The pin and slot connections between the upper and lower platens and their brackets are such that the upper platen will be normally supported a short distance away from the top 3 of the 90 yoke but may be moved upwardly into contact therewith by the upward movement of the plunger 1. The lower platen may be supported, as above described, at a distance below the upper platen and may be moved 100 upwardly by the plunger 1 into contact with the upper platen.

The device which I have provided for holding the lower platen in a position separated from the upper platen and also from the plunger when the plunger is lowered and for holding the lower platen in engagement with the upper platen when the plunger is lowered, is constructed, arranged and operated as follows: Two front fixed posts 15, 114

16, and two rear fixed posts 17, 18, depend from the table 8 and normally rest upon the bottom 4 of the yoke. These posts serve to limit the downward movement of the lower 5 platen 7 away from the upper platen 6 and support the said lower platen as the plunger 1 continues its downward movement. Two front posts 19, 20, and two rear posts 21, 22, depend from their respective levers 23, 24, 10 25, 26, pivoted to the fixed posts 15, 16, 17, 18. These posts 19, 20, 21, 22, are longer than the posts 15, 16, 17, 18, and are connected to be moved into and out of position to rest upon the bottom 4 of the yoke. This 15 is accomplished by connecting the levers 23, 25, by a connecting rod 27, and the levers 24, 26, by a connecting rod 28. The rod 27 is so connected to the levers 23 and 25 that their posts 19 and 21 respectively are simultaneously moved in opposite directions into and out of position and the rod 28 is similarly so connected to the levers 24 and 26 that their posts 20 and 22 respectively are simultaneously moved in opposite directions into and out of position. When the 20 posts 19, 20, 21, 22, are moved into position to rest upon the bottom 4 of the yoke, the lower platen 7 will be held in contact with the upper platen 6, while the upper platen 30 is still separated from the top 3 of the yoke.

A common manually controlled means for swinging the posts 19, 20, 21, 22, into their operative position is provided, which means comprises an inwardly and outwardly sliding rod 29 provided with a handle 30 at its outer end and connected at its inner end to the rods 27, 28, by diagonal bars 31, 32. The posts 19, 20, 21, 22, are normally held out of their operative position by means of 35 a spring 33 interposed between the handle 30 and an abutment 34 on the extension 9 of the table 8 tending to move the handle outwardly to the limit of its movement in that direction.

40 The upper and lower platens are heated by any suitable means such, for instance, as banks of gas burners 35, 36, leading to a suitable source of fuel supply.

Proceeding to describe the operation of 45 the device; the plunger 1 is first raised, lifting the lower platen into contact with the upper platen. The posts 19, 20, 21, 22, are then moved into engagement with the bottom 4 of the yoke for supporting the lower 50 platen in its engagement with the upper platen. The plunger 1 may then be returned to its normal position. The two platens are then heated to the desired temperature, the surface contact between the 55 platens serving to insure a more uniform heating of the two, and because of the platens being separated from the plunger and the top of the yoke, a minimum amount of heat is transferred from the platens to 60 the said parts. After the platens have been 65

heated to the desired temperature, the plunger 1 is again raised and as it takes the load of the lower platen from the posts 19, 20, 21, 22, which form the temporary support therefor, these posts will be automatically moved out of their operative position by the 70 spring 33. The plunger is then lowered permitting the lower platen to separate from the upper platen, a sufficient distance to permit the insertion of the plate between 75 the two platens. The plunger is then again raised first forcing the lower platen upwardly toward the upper platen and finally raising both of the platens up until the upper platen engages the top of the yoke, when 80 the pressing operation is completed. The plunger is then again lowered first permitting both platens to move downwardly a short distance together and then the lower platen to move a short distance downwardly 85 away from the upper platen to permit the removal of the plate. The cycle of operations may then be repeated.

While I have described my invention in connection with a hydraulic press, it is to be understood that it is applicable to any power press. Furthermore, while I have described the operation of the device in connection with a printing plate, it is to be understood that I do not limit the invention to such use 90 but contemplate its use in connection with any work to which it is applicable. It is also evident that various changes might be resorted to in the construction, form and arrangement of the several parts without departing from the spirit and scope of my invention; hence I do not wish to limit myself 95 strictly to the structure herein set forth, but 100

What I claim is:—

1. In a power press, a yoke, a plunger, upper and lower platens interposed between the top of the yoke and the plunger, heating means for the platens and means for normally holding the lower platen separated from the plunger. 105

2. In a power press, a yoke, a plunger, upper and lower platens interposed between the top of the yoke and the plunger, heating means for the platens and means for normally holding the upper platen separated from the top of the yoke. 110

3. In a power press, a yoke, a plunger, upper and lower platens interposed between the top of the yoke and the plunger, heating means for the platens and means for normally holding the lower platen separated from the plunger and upper platen separated from the top of the yoke. 115

4. In a power press, a yoke, a plunger, upper and lower platens interposed between the top of the yoke and the plunger, heating means for platens and means for normally holding the platens separated from each other and from the plunger and top of the yoke. 120 125 130

5. In a power press, a plunger, upper and lower platens, means for normally holding the platens separated from each other, and from the plunger and a manually operated device independent of the plunger for holding the platens together. 30
6. In a power press, a plunger, upper and lower platens, heating means therefor, means for normally holding the platens separated 10 from each other and from the plunger, and a manually operated device independent of the plunger for holding the platens together. 35
7. In a power press, a plunger, upper and lower platens, heating means therefor and means for holding the platens together and separated from the plunger. 15
8. In a power press, a plunger, a yoke, upper and lower platens, heating means therefor and means for holding the platens together and separated from the plunger, and the top of the yoke. 20
9. In a power press, a plunger, upper and lower platens, a stationary support for the lower platen arranged to hold it in a position 25 separated from the upper platen and from the plunger and a manually operated movable support arranged to be brought into position to hold the lower platen in contact with the upper platen.
10. In a power press, a plunger, upper and lower platens, a stationary support for the lower platen arranged to hold it in a position separated from the upper platen and from the plunger, a manually operated movable support arranged to be brought into position to hold the lower platen in contact with the upper platen, and means for automatically throwing the movable support out of its operative position. 30
11. In a power press, a plunger, upper and lower platens, a stationary support for the lower platen arranged to hold it in a position separated from the upper platen and from the plunger, a manually operated movable support arranged to be brought into 40 position to hold the lower platen in contact with the upper platen, and means for automatically throwing the movable support out of its operative position when the plunger takes the load off of said movable support. 45

In testimony, that I claim the foregoing as my invention, I have signed my name in presence of two witnesses, this thirteenth day of April 1911.
